UNITED STATES PATENT OFFICE.

FRANCIS S. INCO, OF LOS ANGELES, CALIFORNIA.

FOLDING BED.

Application filed December 22, 1921. Serial No. 524,078.

To all whom it may concern:

Be it known that I, FRANCIS S. INCO, a citizen of the United States, residing at Los Angeles, in the county of Los Angeles and 5 State of California, have invented a new and useful Improvement in a Folding Bed, of which the following is a specification.

This invention relates to that type of bed which may be folded and moved into places 10 of concealment.

It is an object of my invention to provide a bed mounted upon a wheeled carriage in such a manner that it may be caused to assume a position suitable for placing in a 15 closet or other concealing chamber.

It is a further object of my invention to provide a carriage for such a bed which may be economically, yet sturdily constructed.

Other objects and advantages will be 20 made evident hereinafter.

Referring to the drawings which are for illustrative purposes only:

Fig. 1 is an elevational view of a bed embodying my invention intended for concealment within an article of furniture, such as 25 a davenport, the bed being shown in entirely folded position ready for concealment.

Fig. 2 is a view, similar to Fig. 1, showing the bed in one of the stages of unfolding.

Fig. 3 is also a view taken similarly to Fig. 4 but showing the bed unfolded.

Fig. 4 is a fragmentary plan view of the bed as shown in Fig. 3.

The bed frame 70, is adapted to be folded in such a manner as to provide an enclosed space 71 in which the mattress is contained and which may be tilted into the position shown in Fig. 1 so that it may be concealed 35 by a davenport. The spring frame 70 is constructed of a pair of longitudinal head bars 72, a pair of longitudinal foot bars 73 and link bars 74 joining the bars 72 and 73, these bars preferably being light structure 40 angles. A head spacing angle 75 connects between the ends of the bars 72 and an angle 76 connects between the ends of the bars 73, there being provided a U-shaped supporting bar 77 which pivots between the 45 links 74 so that the cross connecting portion 78 will be entirely clear to the spring when the spring is depressed due to weight thereupon. The feature of pivoting the member 77, allows same to be folded back between 50 the links 74 and out of the way when the bed is in the position shown in Fig. 1. A head 55

frame 80 is pivoted at 81 to upright angles 82 mounted upon the bars 72 at 83 and reinforced by diagonal bars 84. Links 85 connect between pivots 86 upon the head 60 frame 80 and link mountings 87 mounted upon cross bars of the carriage 89. In revolving the bed frame upon the pivot 90 from the position shown in Fig. 1 to the position shown in Fig. 2, the head frame 80 is 65 caused to assume a position perpendicular to the bed frame 70, due to the action thereupon of the link 85. From the position shown in Fig. 2 the spring member 70 may be unfolded to the position shown in Fig. 3, 70 the foot frame 91 which is mounted upon links 92 and 93 being moved from a closed position between the angles 73, through the position indicated by the dotted line 94, to the upright position shown in full lines in 75 Fig. 3, constituting in this position legs 95 for supporting the foot portion of the bed frame.

Pivoted upon the links 74, at a point indicated at 96, are placed intermediate 80 supporting legs 97 having links 98 extending between the upwardly projecting portion 99 thereof and the pivot 90 upon which the entire bed frame 70 swings. In the folding of the bed the links 74 turn on the 85 pivot 101, by which they are attached to members 72, from the horizontal position shown in Fig. 3, to an upright position as shown in Fig. 2. As the links 74 swing upward, the pivots 96 are carried into positions closer to the pivot 90, while the pivot 102 is maintained at a given distance from the pivot 90, owing to the link connection 98 therebetween with the result that the end 99 of the leg 97 is moved relatively 90 outward causing the leg 97 to swing into retracted position shown in Fig. 2. When the spring frame 70 is tilted back from the position shown in Fig. 2 to the position shown in Fig. 1, the relative position of 100 the legs 97 and the links 98 are not changed as the structure comprising the frame 70 merely revolves around the pivot 90. The action of the link 85 serves to maintain the head frame 80 in a substantially vertical 105 position against the folded members 73, as indicated in dotted lines at 105 in Fig. 1. The construction of the carriage 89 provides end frames 106 having cross bars 104 and 107 thereupon; a tie bar 109 reinforced 110 with diagonal members 110; and supporting column members 111, extending ver-

tically from the tie bar 109 to coact with the cross bar 104 in pivotally supporting the bed frame 70.

This application is a continuation, in part, of my application #458,885, filed April 6, 1921.

I claim as my invention:

1. In a bed, the combination of: a bed frame having three portions joined at two pivot points; means for supporting said bed frame so that said three portions may be extended to form a substantially plane surface upon which a mattress may be placed, said pivot points being so formed that the two end sections may be folded over in substantially parallel relationship to enclose the mattress therebetween; a head frame pivoted to one of said end sections; pivot members forming a part of said means for supporting said bed frame so placed that said bed frame may be swung about said pivot members when said bed frame is so folded; and means for swinging said head frame over to lock said bed frame in its folded position when it is so swung about said pivots.
2. In a bed, the combination of: a bed frame having three portions joined at two pivot points; means for supporting said bed frame to form a substantially plane surface upon which a mattress may be

placed, said pivots being so placed that said bed frame may be folded so that the two end portions are substantially parallel to each other and form an enclosure in which the mattress may be carried; a head frame pivoted to one of said end portions; and means for folding said head frame over the other end portion to lock same in the closed position.

3. In a bed, the combination of: a bed frame having three portions joined at two pivot points; means for supporting said bed frame to form a substantially plane surface upon which a mattress may be placed, said pivots being so placed that said bed frame may be folded so that the two end portions are substantially parallel to each other and form an enclosure in which the mattress may be carried; a head frame pivoted to one of said end portions; pivot bolts forming a part of said supporting means about which said bed frame may be turned in its folded position; and means by which said head frame assumes a parallel position outside the other of said end portions thus locking it in place as said bed frame is swung about said bolts.

In testimony whereof, I have hereunto set my hand at Los Angeles, California, this 14th day of December, 1921.

FRANCIS S. INCO.
